UNITED STATES PATENT OFFICE

DAVID GEDDES, OF BERKELEY, CALIFORNIA

GRAIN WASHING AND DRYING MACHINE

Application filed August 1, 1927. Serial No. 209,913.

This invention relates to an improvement in horizontal grain washing and drying machines. One of the principal objects of the invention is to provide a machine of this character wherein the grain, principally wheat, is thoroughly washed, scoured, aerated, cleaned and dried, so as to be properly conditioned and prepared for tempering for milling purposes, with a minimum amount of breakage and loss of grain.

Another object is to provide a machine of this character in which all smut, wild onion, dirt and the like are freed from the grain during and by virtue of the operation provided, by keeping open the perforated metal pores of the machine by air force while the grain is in the process of being washed and scoured by beaters strongly held to rotate in a circular path thereby overcoming the tendency of centrifugal force to throw the beaters closer to the case at some places than at others.

A further object resides in the provision of a machine having these advantages, which is of simple construction and durability, reliable and efficient in operation, and in relation to capacity and cost, economical in the consumption of power for the amount of grain treated and inexpensive to manufacture.

Other objects and advantages reside in certain novel features of the construction, arrangement and combination of parts which will be hereinafter more fully described and particularly pointed out in the appended claims, reference being had to the accompanying drawings in which

Fig. 1 is an elevation, part of the shell being broken away;

Fig. 2 is a sectional elevation on plane 2—2 of Fig. 1;

Fig. 3 is an end view of the front end of the machine;

Fig. 4 is a section on plane 4—4 of Fig. 1 of the delivery end of the machine;

Fig. 5 is a detail showing the manner of controlling the air supply at each end of the machine; and

Figs. 6 and 7 are respectively a plan and perspective view of the beater construction.

The machine, as a whole, comprises a cylindrical shell having mounted therein an axially arranged power driven shaft on which are mounted near each end fans for forcing air into the inside of the shell, this shaft having also mounted thereon longitudinal beaters arranged to move in a circular path in close proximity to the cylindrical shell. The machine as a whole may be considered as divided into two imperforate end sections and an intermediate section having a perforated bottom.

The grain mixed with an adequate amount of water is introduced into the imperforate section at one end of the machine and the washed and dried grain is delivered at the other end. The rapidly revolving beaters throw the grain as it passes through the machine towards the inside of the shell, along which it moves as a thin layer until it is delivered washed by the water and dried by the air, at the end of the machine.

The machine comprises suitable end castings 1 and 2 having legs 55. To these end castings is secured the shell of the machine, which is preferably made in sections.

Referring to Fig. 4, which shows one of the two end sections, both being of the same general construction, 6 is an imperforate metal ring having a sheet steel lining 7, the ring being braced by ribs 8, and secured to the end casting 2.

Extending into each of the end sections (see Figs. 1, 4 and 5) is a tube 8, bolted to the end casting, and within this tube is a sleeve valve 9, which can be moved in and out by screws 10 and wing nuts 11, mounted on the bearing plate 12, bolted to the end casting 1 or 2 (Fig. 1). The bearing cap 13 can be removed by sliding it longitudinally, an opening in the plate 12 being left for that purpose. The bearing plate 12 is bolted to offsets 15 on the ribs 14 and is thus offset from the end casting leaving an opening 16 between the front plate 17 and the bearing plate 12 (see Fig. 5). By moving the sleeve valve 9, the air supply can be completely controlled.

The central section 18, located between the two end sections is made up of an upper im-

perforate panel 19, preferably having a sheet steel wear lining 20, this imperforate lining extending through about one-third of the circumference of the shell. The remaining two-thirds is made up of panel frames 4 carrying perforated metal screens 21. Mounted on the shaft 40 at the inside end of the air tubes 8, are spider arms 22, carrying at their outer ends beaters 23 (shown in detail in Figs. 6 and 7). The beaters 23 are provided with lugs 24, through which pass bolts for securing the beaters to the spider arms 22. The beaters, as shown in Figs. 6 and 7, are made up of connected sections, some of which are in a plane at an angle to the axis of the machine, so that as they rotate, the grain is conveyed from the entrance to the exit end of the machine. These sections are spaced by webs 25, arranged to provide at their upper ends spaces 26, through which the grain can pass as it moves along the beaters. By this arrangement, the beater sections may be, and preferably are, as shown, made as a single piece integral structure, such as a steel casting, or the beater may be made in sections which are welded together to form a single integral structure. Each beater extends as a whole in a straight line parallel to the axis of the machine, between the spider arms 22 located as shown in Fig. 1. The beaters are secured to the spider arms by bolts or rivets passing through lugs 24 (Fig. 7). As these beaters rotate at high speed, (from 500 to 600 R. P. M.) they are roughly cleaned. Subjected to considerable centrifugal force, and as they rotate in close proximity to the shell, it is essential that means be provided to rigidly hold the beaters in position. Accordingly I provide guy-rods 27, arranged as shown in Fig. 2. These rods are secured at their ends to lugs 28, 28, and extend between the alternate beaters. At each end of the beater arms, i. e., those portions which extend into the imperforate end sections of the machine, there are preferably provided steel wear plates 29, the wear plate at the entrance end of the machine (left hand of Fig. 6) being preferably inclined as shown. The intermediate sections of each beater may also be provided with wear plates if it is found to be desirable.

At each end of the machine and in proximity to the ends of the air tubes 8 are provided fans for forcing air into the inside of the shell.

For this purpose, there is bolted to the spider arms 22, a ring 30, to which are riveted the curved fan blades 31. As shown, the lugs 24 of the beaters extend between the ends of the spider arms 22, and the ring 30, thus forming a strong and compact construction.

As shown in Figs. 1 and 3, the front plate 65 is provided with an opening 32, through

which the grain mixed with water is introduced into the machine.

When the grain is merely dampened, it is desirable to provide additional openings 33, covered by plates, when not in use.

As shown in Fig. 4, a delivery spout 35 is connected to a suitable opening in the end section of the shell. Mounted in this spout is a pivoted valve 36, having an arm 37 which carries a weight 38. By adjusting the weight on the arm, the rate at which the grain flows out can be controlled, while at the same time exit of air is prevented.

This end section might be made, partly at least, of perforated material, but I prefer to make it imperforate, as I find that under the conditions of operation existing in this end section, there is a further scouring action. 39, 39 are plates, extending from end to end of the machine, to direct the material passing through the perforations in the shell, to a suitable collecting means.

In operation, the wheat, or other grain to be washed and dried, mixed with a suitable quantity of water (e. g. in some cases 15 gallons of water to a bushel of wheat) is flowed into the imperforate end section of the machine through the opening 32. It is there caught up by the beaters and thoroughly washed in this imperforate section, the whole mass being thrown out by the centrifugal action towards the inside of the shell. The grain is by impact with the beaters thoroughly cleaned.

The whole mass of water, grain and scourings then passes into the central perforated section of the machine, where the water is permitted to escape through the perforated screen. It will be noted that it is impossible for any grain, which may fall into the central portion of the machine, to pass out through the tube 8, as it would there meet the incoming draft of air to the fan. In practice, the greater portion of the water is removed in the first foot or two of its passage over the perforated screen, so that the grain becomes drier and drier as it progresses through the machine.

At the same time a strong current of air is driven into each end of the machine by the fans. The air is sucked in by the action of the fans through the openings 16 (see Figs. 1 and 5) and tubes 8 leading to the eye of the fan in an amount which can be controlled by the valves 9.

The forcible air current not only dries and aerates the wheat, but by its pressure tends to force the water carrying the scourings with it out through the screen perforations, thus tending to keep the openings free. It will be noted that practically the only exit for the air is through the perforated screen section. The control of the air supply is an important feature of my invention, since it enables the operator to control the moisture

conditions, as may be desired. Thus soft wheat, or such wheat as readily absorbs moisture, may need more air to dry it to the extent desired than a harder wheat. The air at the entrance end of the machine, coming into direct contact with the water is dampened while the air sucked in at the delivery end is dry air and comes into contact with already partly dried grain, and as both sources of air supply are under control, the conditions can be exactly adjusted to meet the particular requirements.

The grain after passing through the central section of the machine passes into the end section which may be imperforate, and is delivered through the valve-controlled spout whereby is provided another control means both for the rate of grain delivery and to prevent exit of air. The operator can thus by proper adjustment of these several control devices, accurately adjust the machine, to not only remove the adhering dirt, smut, wild onion and the like, but deliver the grain with a determined amount of moisture.

For convenience the machine has been referred to as divided into end sections and a central section, since a separate operation is performed in each so-called section. Thus the end section at the entrance end of the machine, is a practically closed annular chamber whose inner wall is the tube 8, the outer wall is the imperforate ring 6, the front end wall is the casting 1, and the other end wall is formed by the rotating fan ring to which are connected the beaters, the ends of which project into this practically closed annular chamber. In this section the principal washing is effected. In the other end section the operation is to scour and polish the grain.

It will be understood that the drawings illustrate one specific form of machine, but obviously my invention includes changed constructions, such as an increase in length or diameter of the machine, the use of a greater or less number of beaters, or other modifications within the spirit of my invention.

I claim:

1. The method of washing and drying grain which consists in washing and scouring the grain by forcible impact in the presence of water, delivering the mass of water, grain and impurities into a closed chamber in which it is subjected while under continued forcible impact to the action of a forcible air current, removing the water and impurities and then further scouring the grain by impact in the absence of water in a closed chamber under maintained air pressure.

2. A machine for washing and drying grain comprising a casing having imperforate end portions and an intermediate portion, a shaft extending through the casing, longitudinally extending axially inclined beaters mounted on said shaft and extending

into proximity to said casing, openings in each end of the casing, tubes extending from such openings into the casing, and fans located about the ends of said tubes and arranged to force air into the casing, the intermediate portion of the casing having a perforated bottom.

3. A machine as claimed in claim 2 in which the tubes are provided with valves to control the air supply.

4. A machine for washing and drying grain comprising a casing, a shaft extending therethrough, longitudinally extending beaters, spider arms connected to said beaters and to said shaft and guy-rods connecting said beaters intermediate said spider arms.

5. A machine as claimed in claim 4 in which the guy-rods are cross-connected to alternate beaters.

6. A machine for washing and drying grain comprising a casing, a shaft extending therethrough, longitudinally extending beaters connected to and carried by said shaft, each beater comprising end portions and longitudinally extending intermediate portions inclined to the axis of said shaft, the portions being connected by webs of less depth than the said end portions and intermediate portions.

7. A beater for grain washing and drying machines comprising end portions and inclined intermediate portions and reinforcing plates on said end portions.

8. A beater for grain washing and drying machines comprising end portions and inclined intermediate portions, the portions being connected by webs of less depth than the said end portions and inclined intermediate portions.

9. A beater for grain washing and drying machines comprising end portions, inclined intermediate portions and connecting web portions, and spaced lugs on said beater adapted to serve as connections for supporting arms and guy-rods.

10. A machine for washing and drying grain comprising a casing, a shaft extending therethrough, two sets of spider arms having beaters secured thereto, rings also supported on said spider arms and fan blades secured to said rings, and means for conducting the air through the openings in said rings.

11. A machine for washing and drying grain comprising a casing, a shaft extending therethrough, two sets of spider arms having beaters secured thereto, rings also supported on said spider arms and fan blades secured to said rings and valve controlled means for conducting the air through the openings in said rings.

12. A machine for washing and drying grain comprising a casing, a shaft extending therethrough, a fan having annularly arranged blades mounted on said shaft, and means for introducing air into the eye of a

fan comprising a front plate having an opening therethrough, a bearing plate spaced from said front plate to provide an opening therebetween, a tube extending from said plate to the fan and a valve for controlling said opening.

13. A machine as claimed in claim 12 in which the valve consists of a sleeve within the tube and adjustable means for moving said sleeve to control the size of the opening.

14. In a machine for washing and drying grain comprising a casing having a shaft extending therethrough, two sets of spider arms mounted on said shaft and spaced from the ends of the casing, said spider arms carrying at their outer ends annular fans and beaters extending longitudinally the length of the casing, tubes for admitting air extending into and of the same diameter as the eyes of the fans, thereby dividing the interior of the casing into three sections, an opening for introducing grain and water into the first section, said section having outer imperforate walls, the second section having its lower portion formed as a perforated screen, and the third section having a grain delivery spout.

15. A machine as claimed in claim 14 in which the air tubes and the delivery spout are provided with adjustable valves.

16. A machine for washing and drying grain comprising a casing having end portions and an intermediate portion having a perforated bottom, a shaft extending through the casing, longitudinally extending beaters mounted on said shaft and extending in proximity to said casing, openings in each end of the casing, tubes extending from said openings into the casing, and fans located about the inner ends of said tubes, and valves cooperating with said tubes to control the air supply.

17. A machine for washing and drying grain comprising a casing, a shaft extending therethrough, longitudinally extending beaters arranged to extend into proximity to said casing, each beater comprising end portions and an inclined intermediate portion, the portions being connected by webs of less depth than the beater portions, and spider arms mounted on said shaft to which arms the beaters are secured.

18. A machine for washing and drying grain as claimed in claim 17 having guy rods connecting said beaters intermediate said spider arms.

19. A machine as claimed in claim 4 in which the guy-rods form triangular trusses and are connected to alternate beaters.

In testimony whereof, I affix my signature.

DAVID GEDDES.
